Inventor,

David Henderson Horston

UNITED STATES PATENT OFFICE.

DAVID HENDERSON HOUSTON, OF HUNTER, NORTH DAKOTA.

FOLDING SUPPORT FOR CAMERAS.

SPECIFICATION forming part of Letters Patent No. 694,862, dated March 4, 1902.

Application filed February 8, 1901. Serial No. 46,525. (No model.)

To all whom it may concern:

Be it known that I, DAVID HENDERSON HOUSTON, a citizen of the United States, residing at Hunter, in the county of Cass and 5 State of North Dakota, have invented certain new and useful Improvements in Folding Supports for Cameras; and I do declare the following to be a full, clear, and exact description of the invention, such as will enable others skilled in the art to which it appertains to 10 make and use the same, reference being had to the accompanying drawings, and to the letters of reference marked thereon, which form a part of this specification.

15 My invention relates to folding supports for extending and supporting the front and bellows of folding photographic cameras.

The object of my invention is to provide 20 folding supports suitable for projecting the fronts of folding cameras to a position that will allow the lens carried in the front of the camera to be in a position to be in focus on the sensitized plate or film in the camera. My folding supports are arranged and adapted to 25 be used in extending the bellows and supporting the front and bellows of the camera.

The invention consists in the novel construction and combination of the several parts, as 30 will be hereinafter fully set forth, and pointed out in the claims.

In the drawings similar characters of reference denote similar parts.

Figure 1 is a top plan view of a camera, showing my folding supports connected together and extended in position to support the 35 front of the camera and the bellows. Fig. 2 is a front view of the camera shown in Fig. 1, showing the camera folded, the folding supports being shown folded into the camera-casing 40 going to the position shown by the dotted lines in Fig. 1.

A indicates the camera-casing; B, the camera-front; C, the bellows connecting the camera-front to the camera-casing; D, the folding 45 supports; E, dotted lines showing the position of the folding supports when they are folded into the camera-casing; F, stops against which the folding supports rest when the said folding supports are fully extended; G, dotted 50 lines showing the position of the light-excluding divisions in the camera-casing, to which divisions the inner end of the bellows is

shown by dotted lines to be attached; H, dotted circles showing the position of the guide-rollers that guide the sensitized film 55 over the inner rear ends of the light-excluding divisions; I, the spool-centering device; J, the reel-winding device; K, the folding handle of the reel-winding device; L, the lens; N, the finder-lens; O, the finder; S, the touch-button; V, the recess into which the touch-button recedes; P, knee-joints of the folding supports; R, front pivots of the folding supports; T, rear pivots of the folding supports; X, lugs to which the front ends of the folding 65 supports are pivoted; Y, double lines showing where the casing separates to open the camera.

My invention is intended for use in connection with any style of camera that may be adapted to combine to advantage with my 70 improved folding supports herein specified, and any method of pivoting the front ends of my folding supports to any camera-front may be adopted that is suitable for the purpose, and also any method of pivoting the back 75 ends of my folding supports to any camera-casing may be adopted that is suitable. The front and rear ends being suitably pivoted in proper position, then the knee-joints will fold inward, as shown at the dotted lines in the 80 drawings, Fig. 1, and when the folding supports are extended outward to their full limit the stops (indicated by the dotted lines at F) limit the outward movement of the folding supports and so make a positive position for 85 the folding supports to occupy when fully extended. To fold the front and bellows toward or into the camera-casing, it is simply necessary to slightly press the folding supports inward at their rear knee-joints and 90 then press inward upon the camera-front. Then the folding supports will assume the position shown at the dotted lines in Fig. 1. To extend the camera-bellows and front of the camera forward, simply pull out the camera-front and then press the folding supports against the stops shown by the dotted lines F.

Having fully described my invention, I claim—

1. Combined with a folding camera, four 100 folding supports pivoted respectively to the inner side of the camera-casing and to the camera-front, said folding supports each composed of a long and a short member and each

having a knee-joint adapted to bend inward, and fold into the interior of the camera-casing, substantially as shown.

2. Combined with a folding camera, four folding supports pivoted respectively to the inner side of the camera-casing and to the camera-front, said folding supports each composed of a long and a short member and each having a knee-joint adapted to bend inward, 10 and stops on the camera-casing adapted to stop the folding supports in line when extended.

3. Combined with a folding camera, four pivoted folding supports connecting the camera-front to the camera-casing, the said folding supports each composed of a long and a short member and each having a knee-joint adapted to bend inward and allow the said supports together with the camera-front and 20 extensible bellows to all fold into the interior of the camera-casing, and stops on the camera-casing adapted to stop the said folding supports in line when extended.

4. Combined with a folding camera, four pivoted folding supports, said folding supports each composed of a long and a short member and each having a knee-joint adapted to bend inward, said long members pivoted to the camera-casing equidistant from the center of the said casing, the short members pivoted to the camera-front equidistant from the center of said camera-front, said short members pivoted distant from the center of the camera-front less than the long members are pivoted distant from the center 35 of the camera-casing, said long and short members pivoted in positions on the camera adapted to allow of said long and short members to fold into the camera-casing.

In testimony whereof I affix my signature 40 in presence of two witnesses.

DAVID HENDERSON HOUSTON.
